UNITED STATES PATENT OFFICE

JACOB A. WEBER AND LOUIS A. WEBER, OF CLEVELAND HEIGHTS, OHIO

DESIGN FOR A CATAFALQUE

Application filed December 5, 1929. Serial No. 33,669. Term of patent 14 years.

To all whom it may concern:

Be it known that we, JACOB A. WEBER and LOUIS A. WEBER, citizens of the United States, each residing at Cleveland Heights, in the county of Cuyahoga and State of Ohio, have invented a new, original, and ornamental Design for a Catafalque, of which the following is a specification, reference being had to the accompanying drawing, forming part thereof.

In the drawing, Fig. 1 is a perspective view, showing the front of a catafalque, illustrating our new design, and Fig. 2 is a perspective view showing the back of the catafalque.

We claim:

The ornamental design for a catafalque, as shown.

JACOB A. WEBER.
LOUIS A. WEBER.
